Altona, Germany

Filed Feb. 16, 1959, Ser. No. 793,425

4 Claims. (Cl. 9—338)

The present invention relates to a life jacket and, more particularly, concerns a life jacket in which the buoyancy is produced by a plurality of envelopes or containers filled with air. The said envelopes or containers are so designed and arranged that one envelope or container surrounds the neck of the person equipped with the life jacket primarily in the manner of a collar, whereas the other envelope or container, which may consist of two parts, rests against the chest of said person and is connected with the first mentioned envelope or container so as to form a jacket. The life jacket is furthermore equipped with a bottle or vessel containing compressed air and equipped with a valve communicating with said envelopes or containers. For certain reasons, the volume of said bottle or vessel and the air pressure prevailing therein are so selected that the quantity of air at an outer air pressure of approximately 1 atmosphere will fill a portion only of the total volume of the total envelope or container. The remaining quantity of air required for completely inflating all containers or envelopes has to be provided by oral inflation on the part of the person wearing said jacket.

The container or envelope surrounding the neck of the person has the purpose of securing a swimming position for the person wearing the jacket in such a way that his breathing openings are prevented from immersing in the water and for holding said breathing openings above the water level so that the access of breathing air will be assured.

It is the primary object of the present invention to make sure that the wearer of the life jacket will have the desired swimming position from the very start in spite of the fact that the contents of the bottle or vessel containing compressed air can fill only a portion of the total volume of all of the containers or envelopes.

It is also an object of this invention to provide a life jacket of the above mentioned type, in which that portion of the life jacket which surrounds the neck will be inflated first or primarily before the remaining portion of the life jacket is properly inflated.

It is a further object of this invention to provide a life jacket of the type set forth above, in which means are provided for preventing the air from the jacket portion surrounding the neck of the person wearing the life jacket from passing into other portions of the life jacket.

These and other objects and advantages of the invention will appear more clearly from the following specification in connection with the accompanying drawing diagrammatically showing a life jacket according to the present invention.

The life jacket according to the present invention is characterized primarily in that first the envelope or container portion which is intended to surround the neck is inflated and only thereafter the envelope or container portion surrounding the chest is inflated. To this end, in conformity with the present invention, the connection of the compressed air bottle or vessel with the containers is so designed that a direct conduit of low flow resistance leads from said bottle directly to the envelope surrounding the neck, said conduit being substantially straight and having a branch conduit leading from said conduit to the container surrounding the chest. Means are provided which will offer a greater resistance to the air entering the branch conduit than to the air flowing

2

in the substantially straight conduit leading directly from the compressed air bottle to the envelope forming the neck portion of the life jacket. The said higher resistance in the branch conduit may be obtained for instance by arranging the branch conduit at an angle to the substantially straight or main conduit leading from the compressed air bottle to the neck portion of the life jacket.

With the above arrangement according to the invention, air is prevented from simultaneously flowing into all containers or envelopes after the compressed air bottle valve has been opened. In particular, this arrangement prevents the air from said bottle first to fill the envelope surrounding the chest, even though the conduit from said bottle to the container surrounding the chest is shorter than the conduit leading from the bottle to the neck portion of the life jacket. To the contrary, the arrangement according to the invention brings about that the air from the bottle first almost exclusively or at least to a major extent flows into the neck portion of the life jacket and inflates the same. Only thereafter, i.e. to the extent as the neck portion is being inflated and the resistance in the conduit leading into the same increases, will the remainder of the air pass into the chest portion of the life jacket. Consequently, it will be assured that the buoyancy is first produced in the neck portion of the life jacket which supports the head. In this way, from the very start, the person wearing the life jacket will be placed in proper swimming position in which the person's breathing openings will be held above the water level.

It has proved advantageous, particularly when the main as well as the branch conduit have the same effective inner diameter, to branch the conduit leading to the chest portion of the life jacket off from the main conduit leading to the neck portion of the life jacket at an angle of approximately 90°. If, however, it should be necessary or desirable due to the particular design of the life jacket or for other purposes, the said angle may also be selected less than 90° while in such instance the effective inner diameter of the branch conduit is made less than that of the main conduit. In this way an additional flow resistance will be produced in the branch conduit.

In order to prevent the air in the neck portion of the life jacket from escaping into the chest portion of the life jacket before the chest portion has been orally inflated by the wearer of the life jacket, it is advantageous to arrange a check valve in the main conduit, preferably near the point where it leads into the neck portion of the jacket. Similarly, in the branch conduit leading to the chest portion of the life jacket, a check valve may be provided. Such an arrangement will assure that in case a leak occurs in one of the air containers, no air can escape from the other container.

Inasmuch as these valves offer a certain resistance to the flow of air while the life jacket is being inflated, it is in conformity with the present invention also possible to provide a check valve with lower flow resistance in the main conduit leading to the neck portion of the life jacket, whereas in the branch conduit leading to the chest portion of the life jacket a check valve with higher flow resistance is arranged. Particularly for the main conduit a check valve in form of a flap valve may be selected.

Referring now to the drawing in detail, the life jacket shown therein comprises two inflatable envelopes or containers 1 and 2 of elastic material such as rubber or synthetic material. The upper container or envelope 1 has the shape of a collar and is intended to surround the neck of the person wearing the life jacket. The buoyancy of said neck portion of the life jacket will maintain the head of the person wearing the life jacket in swimming position above the water level thereby assuring that the breathing openings of said person will always be kept

free. The envelope or container 2 forms the chest portion of the life jacket and creates a further buoyancy in the desired swimming position of the person wearing the life jacket. Both containers or envelopes 1 and 2 are mounted on a supporting member 3 common thereto on which also those means (not shown) for connecting the jacket to the body of the wearer thereof may be fastened. The lower portion of said supporting member 3 has connected thereto a bottle or vessel 4 filled with compressed air and equipped with a hand valve 5. A pressure conduit 6 representing the main conduit leads from bottle 4 or its valve 5 directly to the upper envelope 1. Adjacent the point where said main conduit leads into the neck portion 1 of the life jacket, there is arranged in said main conduit 6 a check valve 7, preferably of the flap valve type. Conduit 6 has a slight bend near valve 5 and then extends substantially along a straight line into the neck portion of the life jacket. From the straight portion of main conduit 6 there branches off a branch conduit 8 leading into the chest portion 2 of the life jacket. Also the branch conduit 8 has arranged therein a check valve 9 preferably in form of a flap valve. Conduits 6 and 8 have substantially the same effective inner diameter. The angle at which branch conduit 8 branches off from conduit 6 is approximately 90°. However, if desired or necessary, this angle may also be less than 90° in which instance preferably the effective inner diameter of branch conduit 8 is somewhat less than the inner effective diameter of main conduit 6. At any rate, the effect will be obtained that the compressed air flow from the opened bottle 3 will take the path of least resistance through main conduit 6 in spite of the fact that the latter is longer than the branch conduit 8 and thus will first flow into and inflate container 1. To the extent to which during this inflation the flow resistance will increase in conduit 6, the air will also pass through conduit 8 into the chest portion 2. Depending on the high pressure of the air in bottle 3, the above mentioned inflating process will be carried out rather fast, however, under all circumstances, in the sequence mentioned above. This effect may be further aided if the flap valve 9 is given a higher flow resistance than the flap valve 7.

For completely inflating the chest portion 2 of the life jacket, the latter is provided with a flexible hose 10 of such a length that its free end carrying the mouthpiece 11 can easily be reached by the mouth of the person wearing the life jacket. In hose 10 there is likewise arranged a flap valve 12 forming a check valve.

It is, of course, to be understood that the present invention is, by no means, limited to the particular construction shown in the drawing but also comprises any modifications within the scope of the appended claims.

Thus, instead of compressed air, also any other gas as for instance carbonic acid, may be employed for inflating the containers 1 and 2.

What I claim is:

1. A life jacket having a support for connection with the upper body portion of a person and comprising: a first

inflatable container in the form of a collar connected to said support and forming the neck portion of said life jacket for receiving and floating the neck of the wearer of said life jacket in the water, a second inflatable container connected to said support and forming the chest portion of said jacket for floating the upper body portion of the wearer of said life jacket in the water, a compressed gas containing vessel likewise connected to said support for releasing gas under pressure to said inflatable

- 5 containers, a first conduit leading from said vessel along a nearly straight line into said first inflatable container, and a second conduit branching off from said first conduit at such an angle that the flow resistance at the branching off point of said second conduit to the flow of compressed gas from said vessel into said second conduit during the initial inflating phase is higher than the flow resistance offered by said first conduit to the flow of compressed gas from said vessel into said first inflatable container during said first inflating phase.
- 10 2. A life jacket having a support for connection with the upper body portion of a person and comprising: a first inflatable container in the form of a collar connected to said support and forming the neck portion of said life jacket for receiving and floating the neck of the wearer of said life jacket in the water, a second inflatable container connected to said support and forming the chest portion of said jacket for floating the upper body portion of the wearer of said life jacket in the water, a compressed gas containing vessel likewise connected to said support for releasing gas under pressure to said inflatable
- 15 containers, a first conduit leading from said vessel along a nearly straight line into said first inflatable container, and a second conduit branching off from said first conduit at such an angle that the flow resistance at the branching off point of said second conduit to the flow of compressed gas from said vessel into said second conduit during the initial inflating phase is higher than the flow resistance offered by said first conduit to the flow of compressed gas from said vessel into said first inflatable container during said first inflating phase.
- 20 3. A life jacket having a support for connection with the upper body portion of a person and comprising: a first inflatable container in the form of a collar connected to said support and forming the neck portion of said life jacket for receiving and floating the neck of the wearer of said life jacket in the water, a second inflatable container connected to said support and forming the chest portion of said jacket for floating the upper body portion of the wearer of said life jacket in the water, a compressed gas containing vessel likewise connected to said support for releasing gas under pressure to said inflatable
- 25 containers, a first conduit leading from said vessel along a nearly straight line into said first inflatable container, and a second conduit branching off from said first conduit at such an angle that the flow resistance at the branching off point of said second conduit to the flow of compressed gas from said vessel into said second conduit during the initial inflating phase is higher than the flow resistance offered by said first conduit to the flow of compressed gas from said vessel into said first inflatable container during said first inflating phase.
- 30 4. A life jacket having a support for connection with the upper body portion of a person and comprising: a first inflatable container in the form of a collar connected to said support and forming the neck portion of said life jacket for receiving and floating the neck of the wearer of said life jacket in the water, a second inflatable container connected to said support and forming the chest portion of said jacket for floating the upper body portion of the wearer of said life jacket in the water, a compressed gas containing vessel likewise connected to said support for releasing gas under pressure to said inflatable
- 35 containers, a first conduit leading from said vessel along a nearly straight line into said first inflatable container, and a second conduit branching off from said first conduit at such an angle that the flow resistance at the branching off point of said second conduit to the flow of compressed gas from said vessel into said second conduit during the initial inflating phase is higher than the flow resistance offered by said first conduit to the flow of compressed gas from said vessel into said first inflatable container during said first inflating phase.
- 40 5. A life jacket according to claim 1, in which the inner diameter of said first conduit is greater than the inner diameter of said second conduit.

- 45 6. A life jacket according to claim 1, in which each of said conduits near the respective container into which they lead has mounted therein a check valve in the form of a flap valve.
